ELECTRICAL CONNECTOR

Clarence J. Cihlar, Richmond, Ind., assignor to
 Belden Manufacturing Company, Chicago, Ill.,
 a corporation of Illinois

Application March 30, 1938, Serial No. 198,795

1 Claim. (Cl. 173—322)

5 My invention relates to electrical connectors and has particular relation to detachable plug connectors of the type used for connecting electrical conductor cords to electrical appliances, such as toasters, flat irons, and the like.

10 Connectors of this type usually comprise a hollow, elongated body of insulating material having a plurality, most frequently two, socket type contacts supported in suitable open ended recesses formed therein. The individual conductors of the conductor cord with which the connector is used are attached to these socket type contacts within the insulating connector body by suitable screws or the like.

15 During use of conductor cords fitted with connectors of this type, it is very common practice for the user to effect the disengagement of the connector from the cooperating contact pins or the like forming a part of the appliance with which the connector is used by jerking or pulling the conductor cord. In substantially all of the connectors heretofore known to the art, the stresses resulting from this pulling or jerking of the cord have been applied directly to the electrical connection between the cord conductors and the connector contacts with the result that injury to the connector, or its connections, or even to the user have occurred. Further, repeated application of such stresses tend to wear 20 the cord insulation and create a serious fire hazard.

25 In fact, the potential dangers and hazards of these older type connectors are so great that the insurance underwriters have recently promulgated a rule which provides, in effect, that connectors of this type must be capable of sustaining a weight of fifty pounds applied between the contacts and the associated conductor cord for a period of five minutes without permitting separation of the cord conductors and the contacts even when the contact screws have been backed off sufficiently to substantially disconnect the conductors from the contacts.

30 This rule necessarily requires that connectors of the subject type must include a strain relief means for relieving the electrical connections from mechanical stresses during use, and the principal object of the present invention is to provide an improved strain relief for use in conjunction with connectors of this general type which will inherently prevent the tensional stresses which may be impressed upon the conductor cord during use from being transmitted to the electrical connection between the cord conductors and the connector contacts. As will

hereinafter appear, the improved strain relief means of the present invention also accomplishes the further function of preventing lateral displacement of the component parts of the connector body. Other objects of the invention are 5 to provide an improved means for finishing the ends of conductor cords which shall facilitate the assembling of those cords into the insulating bodies of the connectors with which they are used; to provide an improved strain relief and cord finishing method which shall be relatively 10 simple and inexpensive to practice and which may be utilized in conjunction with existing types of connector structures with no more than slight modification thereof; to provide an improved strain relief and cord finishing arrangement which shall utilize no metallic parts whatsoever, thereby minimizing insulation stresses and fire hazards; and, generally, to provide an 15 improved strain relief and connector embodying 20 the same.

25 Referring to the single sheet of drawings wherein two preferred embodiments of the invention are illustrated—

Figure 1 is a perspective view of an electrical 25 connector of the general type to which the present invention is particularly applicable;

Figure 2 is a sectional view on the general line 2—2 of Figure 1;

30 Figures 3, 4, and 5 are fragmentary views illustrating three steps in preparing the ends of a conductor cord in accordance with the present invention;

Figure 6 is a sectional view illustrating an intermediate step in the assembling of a conductor 35 cord and connector embodying the present invention;

Figure 7 is a fragmentary sectional view on the general line 7—7 of Figure 6;

Figure 8 is a view similar to Figure 6 showing 40 the connector and cord assembled in one of the halves of the insulating body; and

Figure 9 is a fragmentary view, similar to Figures 3, 4, and 5, illustrating a second method of preparing a conductor cord for use with a connector embodying the present invention.

45 The body of the connector illustrated in the drawing comprises two cooperating half sections 11 which are adapted to be securely held together when the connector is assembled by a pair 50 of stiff, U-shaped springs 13 which engage and fit within suitable recesses 15 formed in the sides of the sections 11. The opposed faces of the two cooperating half sections 11 are hollowed out so as to define in the assembled connector two elong- 55

gated recesses 17 for receiving and positioning two socket type contacts 19 which are adapted to cooperate with contact pins or the like forming a part of the appliance with which the connector is used.

The contacts are of the conventional socket type such as are illustrated in U. S. Letters Patent No. 1,954,859, April 17, 1934, to Andre, and the recesses 17 are preferably so formed that the socket contacts 19 are securely held against movement relative to the plug body when the connector is assembled. The recesses 17 are, of course, open at the lower end of the plug body, as is illustrated in Figure 1.

15 The conductor cord 21 illustrated in the drawing is of the usual duplex or two conductor type provided with a braided outer covering. Each of the conductors 25 making up the conductor cord 21 includes a metallic cable 23 surrounded by a suitable insulating sheath. The conductor cord 21 is admitted to the interior of the connector body through a generally cylindrical cord receiving passageway 27 extending inwardly into the central portion of the upper end of that body. The inner end of the cord receiving passageway connects with the two contact receiving recesses 17 through suitable curved branch passageways 29, each of which is adapted to receive the end portion of one of the two conductors 25 making up the conductor cord 21.

20 To minimize bending and kinking of the conductor cord adjacent the connector body, the connector preferably includes an axially flexible protector spring 31 the lower coils of which are adapted to be fastened to the connector body as by engaging the annular recess 33 formed as an enlargement of the cord receiving passageway 27. A ferrule 35 may be provided at the outer end of this protector spring for engaging 25 the cord proper.

In carrying out the present invention, the co-operating halves 11 making up the connector body are provided with cooperating opposed recesses 37 or equivalent means which support a 30 member such as the pin 39 so that it extends across the cord receiving passageway 27, preferably adjacent the inner end of that passageway. The pin 39 or like member is preferably of insulating material and is preferably provided with 35 conically shaped or otherwise pointed ends. As will hereinafter appear, the pin 39 provides a convenient means whereby the connector cord 21 may be mechanically connected to the connector body so as to provide a strain relief for 40 the electrical connections of the connector. In addition, the pin 39 serves to mechanically interconnect the two halves 11 of the connector body so as to prevent lateral displacement of the body halves in the region of the pin 39 during use of 45 the connector. The pin 39 or equivalent member should, of course, be of such dimensions that it does not more than partially close the cord receiving passageway.

Prior to the assembling of the connector, the 50 braided covering of the conductor cord 21 is removed for a short distance so as to permit separation of the two conductors 25, as illustrated in Figure 3. Then, a suitable length of the metallic cable 23 forming a part of each of the conductors 25 is bared and attached to one of the socket type contacts 19, as is shown in Figure 3. Heretofore it has been customary to thereupon assemble the two half sections 11 of the body about these contacts. the adjacent end 55 of the conductor cord 21 occupying the central

passageway 27 and the branched ends of the cord conductors 25 occupying the branched passageways 29. When so assembled, any force applied to the cord 11 would be transmitted directly to the electrical connection between the cord conductors and the socket contacts, the overcoming of which condition is the principal object of the present invention. In contrast with this, a conductor cord which is to be assembled into a connector provided with a pin 39 or like member 10 extending transversely across the cord receiving passageway within the connector body, in accordance with the present invention, is wound prior to being assembled with cord or thread 39', as is illustrated in Figures 4, 5, and 6, to provide 15 a loop 41 in the conductor cord for engaging the pin 39 or other member which extends transversely across the cord receiving passageway. The engagement of the loop 41 with the pin 39 provides a positive mechanical connection between the cord 21 and the connector body which effectively relieves the electrical connections of the connector from strain during use of the connector.

The cord wrapping or winding 39' is best 25 applied by first winding a suitable number of turns of double ply thread about both of the cord conductors 25 and about the end of the braided covering which remains on the conductor cord 21 after the contacts have been applied thereto, 30 as illustrated at 43 in Figure 4. This wrapping may then be tied, and the individual conductors wrapped for a suitable distance by one of the double threads used in the initial wrapping. The wrapping may be continued with both threads 35 to close the loop 41, as illustrated at 45 in Figure 5, after which it is desirable to wrap the individual threads or cords over the remaining length of each of the individual conductors, as is illustrated in Figure 6. This wrapping over the ends 40 of the conductors adjacent the loop 41 holds the conductor insulation in place and also facilitates the assembling of the connector by making conductor ends easier to handle.

When the conductor cord has been wrapped 45 in this manner, it is assembled into one of the halves 11 of the insulating body by simply pressing the loop 41 over the pointed end of the pin 39, as is illustrated in Figures 6 and 7. The dimensions of this loop 41 preferably should be 50 such that it will tightly grip the pin 39. Next, the socket contacts 19 are located in the recesses 17 provided for them, and the wrapped end portions of the conductors 21 are placed in the branch passageways 29 which connect the central cord receiving passageway 27 with the socket receiving recesses 17. Thereupon, the other half 55 of the connector body is put in position and the retaining springs 13 inserted in the recesses 15 so as to lock the body parts together.

Actual tests of a structure of this type show 60 that it provides a most satisfactory strain relief and constitutes one of the few of such structures to be approved by the Board of Insurance Underwriters. The action of the strain relief pin 39 65 in mechanically interconnecting the body halves 11 so as to prevent lateral displacement of those members effectively prevents relative movement of the several parts of the connector adjacent the strain relief means and adds much to the 70 reliability and useful life of the connector. Moreover, it is much easier to assemble a connector and cord prepared in accordance with my invention than it is to assemble the structures heretofore used in the art. The tapered end on the 75

transverse pin 39 which extends across the cord receiving passageway 27 and the wrapping of the exposed ends of the cord conductors 25 are important features in facilitating the assembling 5 of the cord and connector.

It will be apparent that it is not necessary to extend the wrapping 39' along the entire exposed length of the two conductors 25 making up the cord 21. The invention can be accomplished 10 merely by providing two spaced wrappings 47 or equivalent means for joining the conductors 25 so as to define a loop 49 similar to the loop 41, as is illustrated in Figure 9. It is preferred, however, to continue the wrapping over the entire 15 exposed portions of both of the conductors 25, since this greatly facilitates the assembling of the connector.

Various modifications of the structure and method which have been disclosed in the foregoing will be apparent to those skilled in the art. It is my desire, therefore, that the accompanying claim shall be accorded the broadest reasonable construction consistent with what appears therein and with the prior art.

25 I claim the following as my invention:
In an electrical connector of the class de-

scribed, a pair of cooperating half sections of insulating material assemblable by face to face contact to provide a connector body, said half sections being provided with opposed recesses adjacent one end of the body which define a cord receiving passageway, and a pin member which extends transversely across but only partially closes said cord receiving passageway, said pin member being supported at opposite ends by opposed recesses formed in said cooperating half sections whereby the pin member functions to prevent relative lateral displacement between said sections adjacent said recesses, a pair of contacts supported by said body, a conductor cord having a pair of insulated conductors connected respectively to said contacts, said conductors being positioned in the passageway on opposite sides of the pin member, said conductors being tightly bound together adjacent the pin member at the side thereof facing the contacts with a thread or like wrapping, whereby said pin member functions also as a strain relief to prevent the bound portion of the conductors from being pulled outwardly from the passageway.
